United States Patent Office

Des. 181,505
Patented Nov. 19, 1957

181,505

DINNER PLATE OR SIMILAR ARTICLE

Michael Joseph Szymanski, Camillus, N. Y., assignor to Onondaga Pottery Company, Syracuse, N. Y., a corporation of New York

Application January 9, 1957, Serial No. 44,460

Term of patent 14 years

(Cl. D44—15)

The ornamental designs for a dinner plate or similar configuration showing my new design.

I claim:

The ornamental design for a dinner plate or similar article, as shown and described.

References Cited in the file of this patent

UNITED STATES PATENTS

D. 172,000 Barnhart ----- Apr. 27, 1954